UNITED STATES PATENT OFFICE.

AUGUST HANSEN, OF ABERDEEN, SOUTH DAKOTA.

AUTOMATIC PUNCHING DEVICE.

Application filed November 5, 1921. Serial No. 513,117.

To all whom it may concern:

Be it known that I, AUGUST HANSEN, a citizen of the United States, residing at Aberdeen, in the county of Brown and State 5 of South Dakota, have invented new and useful Improvements in Automatic Punching Devices, of which the following is a specification.

This invention relates to punching devices, particularly to a mechanism of this character designed to be used in an ordinary printing press, and has for its object the provision of a punch which is designated to be disposed upon the front of a printing 10 press and which is type high so as to be engaged by the impression plate of the press for effecting the punching operation without necessitating any adjustment of the impression controlling screws on the printing press. 15

An important object is the provision of a punch of this character which is mounted upon a feed plate secured upon the press platen by means of platen bails such as are used for holding the ordinary tympan upon 20 the platen.

Still another object is the provision of a punch of this character which will automatically operate to punch holes through a large number of sheets of paper, the holes being 25 of any desired number and of any preferred shape, the device being furthermore of such formation that the paper to be punched is fed thereinto in exactly the same manner as paper is fed into the press during an ordinary printing operation.

A still further object is the provision of a punch of this character in which the female die member has associated therewith a slide- 30 able waste carrier which automatically ejects the pieces of paper cut out by the male die at each stroke or closing of the press, the engagement of the impression plate with the punch device operating this waste slide.

Yet another object is the provision of a 35 punching device in which the parts may be readily disassembled for effecting interchanging or whereby to permit of making repairs or adjustments which may be necessary to keep the device in thorough opera- 40 tive condition, a novel clamping means being provided for normally holding the parts in certain relative position.

An additional object is the provision of a 45 punch of this character which will be com- 50 paratively simple and inexpensive in manu-

facture, easy to install and use, rapid in action, durable in service and a general improvement in the art.

With the above and other objects and advantages in view, the invention consists in the details of construction to be hereinafter more fully described and claimed, and illustrated in the accompanying drawings in which,

Figure 1 is a plan view of the feeding 65 plate associated with the platen of a press and showing my punch device associated therewith,

Figure 2 is a cross-sectional view through the platen and feed plate and showing my 70 device in side elevation,

Figure 3 is a cross-sectional view through the platen, feed plate and presser plate of the press showing my device in side elevation 75 but in punching position,

Figure 4 is a plan view of my device alone on a larger scale,

Figure 5 is a side elevation of my punch alone on a larger scale showing it in normal 80 position.

Figure 6 is a longitudinal sectional view therethrough showing it in punching position.

Figure 7 is a bottom plan view illustrating 85 the waste carrier.

Figure 8 is a horizontal sectional view taken just below the impression plate.

Figure 9 is a detail sectional view illustrating the spring holding means for retaining 90 the impression plate in position.

Referring more particularly to the drawings the letter A designates the presser or stationary plate of a printing press and B designates the movable platen. In carrying out my invention I provide an elongated feed plate 10 from the ends of which extend arms 11 upon one of which is pivoted, as shown at 12 a lock bar 13 which has its other end adapted to be secured to the other arm 11 by means of a screw 14 or the like. This feed plate 10 is designed to be secured upon the platen B of the press and to be held thereon by means of the usual platen bails indicated by the letter C. The feed plate 10 carries a side guide 15 which may be disposed in any one of a plurality of holes 16 for providing a side guide for paper fed into the press to be punched.

Associated with the feed plate 10 is the punch proper which includes a base 17 110

- formed with spaced bifurcated arms 18 which are slidably engaged upon the lock bar 13 and held at the desired position thereon by means of suitable set screws 19.
- 5 In disposing the punch proper upon the feed plate 10 it is of course necessary that the screw 14 be removed and the lock bar 13 be swung away from the plate 10 so that the punch proper may be engaged upon the bar 13 after which the latter is swung into initial position and the screw 14 reinserted at the proper place. The base 17 includes a lower portion 20 which is provided on its underside with spaced overhanging guides 21 and which is provided upon its upper side with an off-set bracket portion 22 which defines a slot 23 for the reception of the paper to be punched. Secured at the upper wall of the slot 23 is a guide plate 24 which has its forward edge extending beyond the off-set portion 22 and inclined upwardly whereby to define a flaring entrance to the slot 23. The base portion of the punch proper further includes a die plate 25 which is formed with a hole 26 constituting the female die of the device. The corners of the upper portion of the offset bracket 22 are provided with recesses 27 for a purpose to be described. It should also be stated that the top of the off-set bracket portion 22 is formed with spaced recesses 28 within which are engaged coil springs 29, the bracket portion being furthermore provided with a hole 30 registering with the hole 26 in the die-plate 25.
- 15 Pivoted between ears 31 formed on the base of the punch device is an inverted U-shaped frame 32 which has its upper or right portion engaged by an elongated tongue 33 formed on an impression plate 34 which carries a male die 35 passing through the hole 30 and adapted to be projected through the hole 26. Projecting from the underside of the impression plate 34 are dowel pins 36 which engage the coil springs 29 whereby the impression plate will normally be urged into its uppermost position with the male die disposed out of obstructing relation to the paper receiving slot 23.
- 20 40 In order to limit upward movement of the impression plate with respect to the base of the punch, such upward movement being urged by the spring 29, I provide the impression plate 34 with depending side portions 37 which are slidably engaged against the ends of the offset bracket portion 22 and which terminate in laterally directed flanges 38 engaging against substantially U-shaped spring clips or clamps 39 which are formed intermediate their ends with loops 40 constituting handles and which have the terminals of their arms inwardly directed as indicated at 41 and engaged within the recesses 27 at the corners of the bracket member 22. Ordinarily it will be

seen that the flanges 38 engage against the spring clamp 39 so that the impression plate 34 will be exactly type high.

Slidably mounted between the guides 21 on the lower surface of the base is a waste carrier formed as an elongated plate 42 pivotally connected with the frame 32 as shown at 43, and formed with an elongated slot 44 adapted, at certain times, to register with the hole 26 in the die plate 25 for receiving the pieces of paper cut out by the cooperating male and female dies 35 and 26 respectively. The plate 42 is formed with an upwardly extending ear 45 which is disposed within the frame 32 and which is provided with a hole 46 for the passage of a guide rod 47 which projects from the back of the off-set bracket 22 and which is surrounded by a coil spring 48 which has one end abutting against the bracket and its other end abutting against the ear 45. This spring 48 operates to hold the frame 32 in normal position in engagement with the impression plate 34 as will be readily apparent. At its underside the plate 42 is formed with a transverse rib 49 which is flush with the underside of the base 17.

Assuming that the device has been constructed and assembled as above described and as illustrated in the drawings, the operation is as follows:

The feed plate 10 is secured upon the press platen and is held thereon by means of the bails C. The screw 14 is removed to permit swinging of the bar 13 and the punch proper is disposed in association with this bar 13 by engaging the bifurcated arms 18 upon the bar 13 and securing them in position along the bar at any desired location by means of the set screws 19. The bar 13 is then swung to normal or initial position and the screw 14 is inserted for holding the bar at the proper place rigidly with respect to the plate 10. The side guides 15 must of course be so disposed within one of the holes 16 in the feed plate as to bring the paper fed into the device at the proper point to be punched. As the press is open, paper is fed into the slot 23, being properly guided thereinto by the side guide 15. As the platen of the press is moved toward the stationary or presser plate A thereof, it will be apparent that the engagement of the impression plate 34 against the plate A will cause the impression plate to be moved down into engagement with the off-set bracket 22, owing to the fact that the device is type high, and this will naturally result in forcing the male die 35 through the hole 26 constituting the female die so that a hole will be punched through all the pieces of paper located within the slot 23. As the impression plate 34 is forced toward the base, the engagement of the tongue 33 with the frame 32 will cause the latter to swing upon its pivot and this will

result in forward movement of the waste plate 42 so as to bring the slot 44 therein into registration with the female die hole 26 so that the pieces of paper cut from the sheets 5 being punched will pass into the slot 44. As the press subsequently opens it is apparent that the springs 29 will operate to return the impression plate to normal position, that is force it away from the frame and bracket 10 22, this outward movement being limited by the engagement of the flanges 38 with the spring clamps 39. As this movement of the impression plate occurs it is apparent that the frame 32 will return to its normal position 15 under the influence of the spring 48 and this will result in rearward movement of the waste plate 42 so that the rib 49 thereon will move rearwardly the little pile of small pieces of paper punched from the sheets and 20 owing to the fact that the rear end of the slot 44 is open it will be apparent that the waste pieces of paper will slip out and fall through the press instead of accumulating and clogging the action of the punch. This 25 action is continuous as long as the press is in operation, a punching action being effected every time the press is closed, and the waste paper being automatically discharged at the completion of each stroke of the 30 punch. Owing to the strength of the various parts it is apparent that quite a large number of sheets may be punched at the same time so that the device will be a great time and labor saver in punching 35 paper for ledgers, loose leaf filing systems and the like.

From the foregoing description and a study of the drawings it will be apparent that I have thus provided a simply constructed and consequently inexpensive punch which will automatically operate when used in association with a platen printing press. While I have shown the die members as being circular it is of course to be understood that they may be of any desired shape and that any number of die members may be used. It is also to be observed that in case it is so desired the impression plate 34 may be removed by disengaging the spring 39 from the bracket member 22 by the simple process of disengaging the inwardly directed ends 41 of the clamps from the recesses 27 in the bracket 22. It is also to be observed that I may use a plurality of 45 the punching devices associated with the bar 13 and held thereon at the desired points so that a comparatively large number of punches may be made simultaneously when such is desired. It is also to be noted that 50 the positions of the punch members may be varied along the bar 13 and these positions may be maintained set by means of the set screws 19 which operate to lock or secure the punches at any desired point.

65 While I have shown and described the pre-

ferred embodiment of the invention, it is of course to be understood that I reserve the right to make such changes in the form, construction and arrangement of parts as will not depart from the spirit of the invention 70 or the scope of the subjoined claims.

Having thus described my invention I claim:

1. In combination with the platen of a printing press, a punch device comprising 75 a base member secured at a desired location upon the platen and formed with a hole constituting a female die, an offset bracket member carried by the base and defining therewith a paper receiving slot, said bracket member being formed with a hole registering with said first named hole, an impression plate slidably mounted upon the bracket member and carrying a male die passing through said second named opening and 80 adapted to be projected through said first named opening.

2. In combination with the platen of a printing press, a punch device comprising 85 a base member secured at a desired location upon the platen and formed with a hole constituting a female die, an offset bracket member carried by the base and defining therewith a paper receiving slot, said bracket member being formed with a hole registering with said first named hole, an impression plate slidably mounted upon the bracket member and carrying a male die passing through said second named opening and 90 adapted to be projected through said first named opening, a slotted waste carrying plate slidably mounted within said base portion, and an operative connection between said waste carrying plate and said impression plate whereby to move the former 95 when the latter is pressed toward the base.

3. A punch device of the character described comprising a feed plate adapted to be secured upon the platen of a printing press, a side guide adjustably mounted upon said feed plate, and a punch proper adjustably mounted with respect to the feed plate and comprising a base formed with guides, a die plate carried by the base and formed with a hole constituting a female die, an offset bracket member carried upon the base and defining therewith a paper receiving slot, said bracket member being formed with a hole registering with said first named hole, an upwardly spring pressed slidably mounted impression plate carried by the bracket member, a male die carried by said impression plate and passing through said first named hole, an extension on said impression plate, a slideable waste carrying plate movable between said guides and formed with an elongated slot adapted to register with said first named hole, and a frame pivotally mounted upon the bracket member and pivotally connected with said 110 115 120 125 130

waste plate, said bracket member being engaged by and moved by said extension of the impression plate.

4. A punch device of the character described comprising a feed plate adapted to be secured upon the platen of a printing press, a side guide adjustably mounted upon said feed plate, and a punch proper adjustably mounted with respect to the feed plate and comprising a base formed with guides, a die plate carried by the base and formed with a hole constituting a female die, an offset bracket member carried upon the base and defining therewith a paper receiving slot, said bracket member being formed with a hole registering with said first named hole, an upwardly spring pressed slidably mounted impression plate carried by the bracket member, a male die carried by said impression plate and passing through said second named hole and adapted to be projected through said first named hole, an extension on said impression plate, a slidable waste carrying plate movable between said guides and formed with an elongated slot adapted to register with said first named hole, and a frame pivotally mounted upon the bracket member and pivotally connected with said waste plate, said bracket member being engaged by and moved by said extension of the impression plate, the slot in

said waste carrying plate registering with said first named hole when said impression plate is moved toward the base for causing projection of the male die through the 35 female die hole, and said waste carrying plate being provided on its underside with a transverse rib flush with the lower surface of the base.

5. In combination with the platen of a 40 printing press, a feed plate secured upon the platen and formed with spaced arms, a lock bar pivoted upon one arm and detachably connected with the other arm, a side guide adjustably mounted upon said feed plate, 45 and a punch member proper slidably adjustably mounted upon said bar and including a base formed with a female die hole, a support carried by the base and formed with a hole registering with said 50 first named hole, and an impression plate slidably and detachably mounted upon said support and carrying a male die passing through said second named hole and adapted to be projected through said first named 55 hole, said impression plate being normally type high and adapted for engagement against the stationary presser plate of the printing press.

In testimony whereof I affix my signature. 60

AUGUST HANSEN.
